UNITED STATES PATENT OFFICE.

HORACE A. CURETON, OF LOS ANGELES, CALIFORNIA.

RADIATOR.

1,240,543.

Specification of Letters Patent. Patented Sept. 18, 1917.

Application filed April 15, 1916. Serial No. 91,459.

To all whom it may concern:

Be it known that I, HORACE A. CURETON, a citizen of the United States, residing at Los Angeles, in the county of Los Angeles and State of California, have invented new and useful Improvements in Radiators, of which the following is a specification.

This invention relates to radiators for internal combustion engines and particularly pertains to that type of radiator known as "honeycomb" which is cooled by the passage of air through air ducts.

It is an object of my invention to construct a radiator of the class described which allows the circulation of water around air ducts at a slow rate of travel, the water being retarded in its flow by the zig-zag configuration of the channel through which it passes so that it will be subjected to the cooling action of the air passing through the air ducts a longer time than in radiators having straight water channels.

Another object is to provide a radiator construction which allows the water to flow therethrough in a thin body, thus facilitating the cooling action of the air thereon.

It is a further object to so form the circulatory system of my radiator that the air will come in direct contact with all the walls which retain the water during its flow through the radiator.

It is another object to so form the water channels that they will have vertical and horizontal portions subject to the action of a current of air passing through adjacent air ducts.

Another object of my invention is to form the vertical walls of the water passages and air ducts at an inclination to the direction of flow of air entering the ducts, so that the air in passing through the radiator will not simply pass through unresisted but will impinge against the inclined walls of the ducts and in so doing increase the cooling action of the air upon the water to a considerable degree.

Another object is to so form the component parts of which the radiator is composed that but one shaped element is required to build the radiator throughout, thus eliminating a number of special dies and the exercise of great care in selecting the proper elements to produce the desired radiator.

Other objects will appear hereinafter.

The invention is illustrated in the accompanying drawings in which:

Figure 1 is a view in side elevation of a portion of the sheet metal element from which my radiator is built, said view disclosing the side of the element with which the air comes in contact.

Fig. 2 is an end view of the element showing the alternate oppositely extending diagonal vertical walls thereof.

Fig. 3 is a view in side elevation illustrating the opposite side of the member disclosed in Fig. 1 and shows the side of the element with which the water comes in contact.

Fig. 4 and Fig. 5 are perspective views of two of my elements showing the air and water sides, respectively, which, taken collectively, illustrate the manner in which the two portions are assembled.

Fig. 6 is a view of a portion of the end edge of the radiator showing the manner in which the elements are telescoped and united.

Fig. 7 is an enlarged view in vertical section taken along a line at approximately the center of the radiator and illustrating the arrangement of the alternately diverging vertical walls of the air ducts and water channels and the horizontal portions of the latter.

Figs. 8 and 9 are horizontal sections taken longitudinally of an assembled section of the radiator and showing the slanting water channels as they are arranged in opposite diagonal relation to each other and further illustrating the diagonal walls of the air ducts.

My invention primarily resides in the configuration of the sheet elements 10 of which my radiator is assembled and also in the manner in which these elements are arranged in relation to each other to form diagonal air ducts.

This element 10 is formed of sheet metal in any desired manner and the blank from which it is made is provided with a series of transverse corrugations, which corrugations are preferably substantially rectangular in cross section and tapered longitudinally with the adjacent corrugations 11 and 12 arranged so that the bottom walls 13 and 14 thereof will extend diagonally to each other and cross intermediate their ends.

In forming the corrugations, a double rib-like wall 15 is formed between the adjacent corrugations on the air side *a* of the sheet, as shown in Figs. 1 and 4. This rib-like wall is U-shaped in cross section with its inner faces spaced apart, as shown in Fig. 7, forming transverse channels 16 between adjacent corrugations on the water side *b* of the sheet, as shown in Fig. 7. The edges of the walls 15 on the air side *a* of the sheet are on the same plane so that when the air sides of a pair of the sheets are disposed face to face, the rib walls on one sheet will seat on the rib walls of the other sheet throughout their lengths.

A corrugation 21 is formed longitudinally of the walls 13 and 14 and is here shown as substantially V-shaped in cross section. These corrugations bear the relation to each other and to the walls 13 and 14 as shown in Fig. 7. In this figure they are shown as forming vertical passage ways or water channels 17 which connect one set of channels 16, formed by the rib-walls 15, to the other. The corrugation 21 provides a means of disposing of a surplus of metal which occurs during the forming operation and also increases the water capacity of the radiator over that of a straight wall channel, and furthermore increases the radiating surface and thereby aids in more readily cooling the water which flows therethrough.

The outer end of the bottom wall of each corrugation extends on the same plane as the opposite end of the adjacent corrugation so that the side edges of the sheet will be of substantially the same thickness overall, as shown in Fig. 2.

As a means for providing a clearance or space between a pair of the sheets when placed with the water sides *b* adjacent each other to form a longitudinally extending water channel 16 and 17, between the sheets, off-sets 18 are formed in the walls 13 and 14 on the water side of the sheet, as shown in Fig. 5.

In assembling the radiator, a pair of sheets are placed with the water sides *b* against each other with the corrugations on one sheet telescoping the corrugations on the other sheet, whereupon the end edges of the sheets are secured together in any desired manner. This forms a radiator section substantially corresponding in shape to a single sheet, this section, however, having the longitudinally extending water channels 16 and 17 extending therethrough. This water channel will be zig-zag in its formation, that is, the channel extending between the contiguous inner walls of a pair of corrugations will extend diagonal to the space between the inner walls of the adjacent corrugation, as illustrated in Figs. 8 and 9. A pair of sections thus formed are then arranged side by side, as shown in Fig. 6,

forming a series of air ducts 19 and 20 arranged so that adjacent air ducts will extend in diagonal relation to each other. By this arrangement the walls 13 and 19 form diagonal impinging walls against which air flowing through the ducts strikes, thereby effecting a more rapid cooling action than where the side walls of the ducts arranged in the direction of the flow of air entering the ends thereof.

In the operation of my radiator, the water passes vertically through the units, as indicated by the arrow *c*, through the water passages 17, then extending outwardly into the channels 16 and from there through succeeding passages 17. In this manner the water will be subjected to the cooling action of the air as it is impinged against the angular surfaces 13 and 14 and also as it envelops the walls of the channels 16. It will thus be seen that the film of water is acted upon by the cooling action of the air against all of its adjacent walls, and that there are no portions of the radiator which come in direct contact with the passing water that are not directly acted upon by the air passing therethrough, the manner in which I have diagonally arranged the water passages increasing the cooling effect of the air thereupon as it retards its passage therethrough and diverts its line of travel, in this way throwing it more forcefully against the adjacent walls.

It will thus be seen that I have provided a radiator construction which will allow the water to pass therethrough at a slower rate of flow than is common, will subject a maximum volume of water to the cooling action of the air and insure that the air acting upon the radiating surfaces will do its work more efficiently than in forms of radiators where the passage of air is unretarded.

What is claimed is:

1. In a radiator, a sheet element formed with longitudinally tapered corrugations substantially rectangular in cross section with adjacent corrugations having opposed diagonally extending bottom walls.
2. In a radiator, a sheet element formed with longitudinally tapered corrugations substantially rectangular in cross section, the adjacent corrugations being tapered throughout their lengths in opposite directions.
3. In a radiator, a sheet element formed with longitudinally tapered corrugations, with the adjacent corrugations tapered in opposite directions in relation to each other, and having a corrugation extending longitudinally between the side walls of the tapered corrugations.
4. In a radiator, a sheet element having longitudinally tapered corrugations with the adjacent corrugations tapered in opposite directions in relation to each other,

- said corrugations having their bottom walls off-set intermediate their ends.
5. In a radiator, a sheet element having longitudinally tapered corrugations with the 5 adjacent corrugations tapered in opposite directions in relation to each other, said corrugations having their bottom walls off-set intermediate their ends, and having rib-like corrugations between the side walls of 10 the tapered corrugations.
6. In a radiator, a corrugated sheet element having the bottom walls of adjacent corrugations inclined in opposite directions to each other.
- 15 7. In a radiator, a corrugated sheet element having the bottom walls of adjacent corrugations inclined in opposite directions to each other, and formed with rib-like corrugations extending lengthwise thereof.
- 20 8. In a radiator, a pair of corrugated sheets adapted to be joined face to face at their edges to form a water passage therebetween, the adjacent corrugations being formed with oppositely inclined bottom walls having outwardly projecting rib-like 25 corrugations extending longitudinally thereof, widening the water passage between the contiguous bottom walls of the main corrugation.
9. A radiator, comprising a pair of corrugated sheets adapted to be joined face to face at their edges to form a water passage therebetween, the adjacent corrugations being formed with oppositely inclined bottom walls having outwardly projecting rib-like 30 corrugations extending longitudinally thereof widening the water passage between the contiguous bottom walls of the main corrugation, said pair of corrugated sheets adapted to be affixed at their edges to a corre- 35 sponding pair of connected sheets to form superposed air ducts between the water pas- sages with adjacent ducts extending dia- 40 ginally in relation to each other.
- In testimony whereof I have signed my 45 name to this specification.

HORACE A. CURETON.
